CLAIM

The ornamental design for a container for holding a catalyst, as shown and described.

DESCRIPTION

FIG. 1 is a perspective view of a container for holding a catalyst showing a new design;

FIG. 2 is a front view of the container illustrated in FIG. 1;
FIG. 3 is a rear view of the container illustrated in FIG. 1;
FIG. 4 is a right side view of the container illustrated in FIG. 1;

FIG. 5 is a left side view of the container illustrated in FIG. 1;

FIG. 6 is a top view of the container illustrated in FIG. 1; and,

FIG. 7 is a rear view of the container illustrated in FIG. 1. The broken lines in the drawings illustrate the portions of the container that form no part of the claimed design.

1 Claim, 4 Drawing Sheets
